J. M. JOHNSON.
THERMOSTATIC CIRCUIT CLOSER.
APPLICATION FILED MAY 1, 1912.

Atty.

UNITED STATES PATENT OFFICE.

JOHN M. JOHNSON, OF KANSAS CITY, KANSAS.

THERMOSTATIC CIRCUIT-CLOSER.

1,113,125.

Specification of Letters Patent.

Patented Oct. 6, 1914.

Application filed May 1, 1912. Serial No. 694,492.

To all whom it may concern:

Be it known that I, JOHN M. JOHNSON, a citizen of the United States, residing at Kansas City, in the county of Wyandotte and State of Kansas, has invented certain new and useful Improvements in Thermostatic Circuit-Closers, of which the following is a specification.

My invention relates to improvements in thermostatic circuit closers, and my object is to provide a novel device of this character which, while susceptible of other uses, is especially adapted for electric fire alarm signals.

One of the features of the invention resides in means whereby the mercurial or other column within the glass tube of the thermostat may expand to an abnormal degree without breaking said tube.

Another feature of the invention resides in means for protecting the glass tube and certain terminals communicating therewith, from destruction or deterioration by outside influences.

Other features of the invention will hereinafter appear, and in order that said invention may be fully understood, reference will now be made to the accompanying drawing, in which:

Figure 1 is a side elevation of my improved device. Fig. 2 is a central vertical section on line II—II of Fig. 1. Fig. 3 is a plan view of the device. Fig. 4 is an inverted transverse section on line IV—IV of Fig.

2. Fig. 5 is a vertical central section of the thermostatic tube and certain terminals communicating with the bore thereof.

In carrying out the invention, I employ a tube 1, consisting, preferably, of glass, or other transparent material, having a bulb 2 at one end and a chamber 3 at its opposite end, which chamber communicates with the bulb through a central longitudinal bore 4, extending through the tube 1.

5 and 6 designate two disconnected terminals of an electric circuit, such for instance, as that disclosed in my copending application for automatic electric fire alarm system, filed May 1, 1912, Serial Number 694,491, or any

other suitable circuit. The lower ends of said terminals 5 and 6 are fused in the lower portion of the tube 1, where they are submerged in mercury or any other fluid conductor 7, which will expand under the influence of

rising temperature. Only a sufficient amount

of fluid 7 is used to fill the bulb 2 and fully submerge the terminals 5 and 6 when the temperature is at zero.

8 designates an upper terminal of a circuit, which terminal is fused in the tube 1, at a point to which the fluid 7 will expand when subjected to a temperature of, say 160 degrees Fahr.

Terminals 5, 6 and 8 extend upward along the tube 1, as shown on Fig. 2, and are connected to conductors 9, 10 and 11, provided, respectively, with depending binding-posts 12, 13 and 14.

Tube 1 and the terminals communicating therewith are protected from breakage by a cylindrical receptacle 15, provided at its upper end with a circular flange 16, carrying the conductors 9, 10 and 11, and their respective binding-posts. Flange 16 has apertures 17 extending therethrough so that it may be readily secured by bolts or screws to a ceiling, or other suitable support. Receptacle 15 consists, preferably, of material, which is fire-proof, a good nonconductor, and impervious to water. The inner diameter of receptacle 15 is sufficiently greater than that of tube 1, to leave an annular space, which is filled with material 18 that is both fire and water-proof, to protect the terminals from corrosion, and also to assist receptacle 15 in protecting tube 1, only a portion of the bulb of which is exposed.

In practice the circuit through the terminals 5 and 6 is normally closed by the fluid conductor 7. Should the device be subjected to a temperature of say 160 degrees, the liquid conductor 7 will expand until the upper terminal 8 is submerged, thereby closing an alarm circuit through terminal 8, the fluid conductor 7 and one of the lower terminals, as set forth in my copending application, above referred to. Should the temperature materially exceed 160 degrees, tube 1 will be prevented from being destroyed by abnormal expansion of the fluid conductor 7 on account of the chamber 3, into which the upper end of the column of fluid flows, thereby relieving said tube 1 of excessive pressure due to said abnormal expansion.

Should the exposed portion of the bulb 2 become broken and permit the fluid conductor 7 to flow therefrom, the circuit through conductors 5 and 6 will become interrupted and actuate a signal, as set forth in my copending application, hereinbefore referred to.

Having thus described my invention what I claim and desire to secure by Letters Patent, is:

- 5 1. In combination, a thermostat receptacle comprising a tube, a base flange on the upper end of the tube, a tubular filling of fireproof, waterproof material within said tube, and a thermostat mercury tube fitted within said filling, said mercury tube having an integral bulb on one end, said bulb being exposed to atmosphere, and electrical contacts communicating with the interior of said mercury tube.
- 10 2. A thermostatic circuit closer, consisting of a tube having a bulb at one end and a chamber at its opposite end, said chamber communicating with said bulb through a bore in the tube, a circuit terminal extending into the lower portion of said tube, a circuit terminal extending into the upper portion of said tube, a fluid conductor in the tube, and a receptacle surrounding said tube except its bulb, which is exposed to atmosphere,
- 15 3. A thermostatic circuit closer, consisting of a tube having a bulb at one end and a chamber at its opposite end, said chamber communicating with said bulb through a bore in the tube, two disconnected circuit terminals extending into the lower portion of said tube, a fluid conductor in the tube establishing communication between said disconnected terminals, a receptacle surrounding said tube and leaving the bulb exposed to atmosphere, conductors carried by said receptacle to which the terminals are connected, and binding posts communicating with said conductors.
- 20 4. A thermostatic circuit closer, consisting of a tube having a bulb at one end and a chamber at its opposite end, said chamber communicating with said bulb through a bore in the tube, two disconnected circuit terminals extending into the lower portion

of said tube, a fluid conductor in the tube establishing communication between said disconnected terminals, a receptacle surrounding said tube, but leaving the bulb exposed to atmosphere, a space being left between the tube and the interior of said receptacle, and insulating material impervious to moisture filling said space, substantially as described.

5 5. In combination, a thermostat receptacle formed of non-metallic fireproof and waterproof material, said receptacle consisting of a tubular portion, a base flange on the upper end thereof, wire-connecting devices mounted on said flange, a tubular filling of fireproof, waterproof material within said tube, a thermostat tube embedded in said filling but having an integral bulb which is uncovered, and electric connections between the thermostat and said wire-connecting devices.

6 6. A thermostatic circuit closer, consisting of a tube having a bulb at one end and a chamber at its opposite end, said chamber communicating with said bulb through a bore in the tube, two disconnected circuit terminals extending into the lower portion of said tube, an upper circuit terminal extending into said tube above the two disconnected terminals, a fluid conductor in the tube establishing communication between the two disconnected terminals and adapted to expand into contact with said upper terminal when subjected to a predetermined temperature, and a receptacle surrounding said tube and adapted to protect same from heat, water, and mechanical breakage, substantially as described.

In testimony whereof I affix my signature, in the presence of two witnesses.

JOHN M. JOHNSON.
